UNITED STATES PATENT OFFICE

118,443

DESIGN FOR AN EASEL OR SIMILAR ARTICLE

Herbert E. Fisk and Katherine E. Dyer,
Chicago, Ill.

Application March 27, 1939, Serial No. 83,850

Term of patent 14 years

To all whom it may concern:

Be it known that we, Herbert E. Fisk and Katherine E. Dyer, both citizens of the United States and both residing in the city of Chicago, in the county of Cook and State of Illinois, have invented a new, original, and ornamental Design for an Easel or Similar Article, for which the following is the specification, reference being had to the accompanying drawing, forming a part thereof.

On the drawing:

Fig. 1 is a perspective view of the easel illustrating the design embodying our invention.

Fig. 2 is a side elevational view of said easel.

Fig. 3 is a front elevational view of the easel of our invention.

We claim:

The ornamental design for an easel or similar article, substantially as shown.

HERBERT E. FISK.
KATHERINE E. DYER.
